United States Patent Office

Des. 195,150
Patented Apr. 30, 1963

195,150

ROLL-ON DISPENSER

Ira H. Miller, Lambertville, Mich., and Edward A. Randlett, Memphis, Tenn., assignors to Owens-Illinois Glass Company, Toledo, Ohio, a corporation of Ohio

Filed Nov. 8, 1961, Ser. No. 67,416

Term of patent 14 years

(Cl. D58—26)

The side and end not shown are substantially like the side and end shown.

We claim:

The ornamental design for a roll-on dispenser, substantially as shown and described.
